DOOR STOPPER

Bronislaus B. Kaminski, Grand Rapids, Mich.

Application January 9, 1948, Serial No. 1,451

5 Claims. (Cl. 292—288)

1

My invention relates to household articles and more particularly to a door stopper.

The object of my invention is to provide a door stopper consisting of a relatively stationary base part supporting a spring biased top part adapted to engage the under edge of a door to secure it in adjusted open position.

Other objects of my invention not specifically mentioned may appear in the following specification describing my invention with reference to the accompanying drawing illustrating a preferred embodiment of my invention. It is however, to be understood, that the invention is not to be limited or restricted to the exact construction and combination of parts described in the specification and shown in the drawing, but that such changes and modifications may be made, which fall within the scope of the claims appended thereto.

In the several figures of the drawings similar parts are designated by similar reference characters and

Figure 1 is a view in side elevation of a door stopper constructed in accordance with the present invention, showing the same in use.

Figure 2 is a top plan view of the same.

Figure 3 is a vertical longitudinal section through the door stopper.

The door stopper forming the subject matter of my invention comprises a relatively stationary base B preferably made in one integral piece and having a base plate 10, from which a substantially cylindrical hollow body 11 extends upwardly. The body is arranged adjacent one end of the base plate and symmetrically about the longitudinal center line of said plate. In the top of the body 11 a central opening 12 is provided leaving an inwardly extending circumferential flange 13 for a purpose to be described later. The circumferential portion of the base plate 10 forms a downwardly open hollow 14. A rubber foot pad 15 has the same contour as the base plate 10, and the circumferential portion of the foot pad is provided with an upwardly extending reinforcement 16 adapted to be pressed into the circumferential hollow 14 of the base plate 10, so that said base plate rests on the foot pad 15 and is prevented from accidentally sliding from said pad.

Since the body 11 is arranged adjacent one end of the base plate, the other end of this plate extends a comparatively long distance beyond the body 11. In the wall of the cylindrical body an axial groove or key way 17 is provided for a purpose to be described later.

A spring retainer R has a substantially cylind-

rical cup-like body 18, on the upper edge of which an outwardly extending circumferential flange 19 is formed. The cylindrical cup-like body of the spring retainer fits slidably into the opening 12 in the top of the base B and the flange 19 on the spring retainer rests on the flange 13 of the base.

A top member T has a substantially cylindrical body 20 fitting slidably over the cylindrical base body 11. On the lower edge portion of the top body 20 a radially extending comparatively broad stop lever 21 is formed, the lower edge of which is arranged at the same level with lower edge of the top body, and the upper surface of which is provided with upwardly extending short teeth 22. A portion of the top body 20 located adjacent the lower edge thereof is pressed inwardly to form a key 23 fitting slidably into the key way 17 in the base body 11 and holds the stopper lever 21 in correct alignment with the large portion of the base plate 10. A helical spring 24 is set into the retainer R and engages the top member T urging it upwardly on the base body 11.

When the above described door stopper is to be used to hold a door 25 in a desired open position, the door stopper is put in the desired place, and the top member is forced downwardly compressing the spring 24. The door 25 is opened so that it extends over the toothed stop lever 21 and the top member is released. The spring urges the top member upwardly, so that the toothed stop lever engages the lower edge of the door 25 securing it in the desired position. The rubber foot pad 15 prevents any accidental sliding movement of the door stopper on the floor.

On the upper end of the key way 17, a shoulder 26 is formed to prevent the top member T from being pushed entirely off the base body 11 by the helical spring 24, when the door stopper is not in use.

I claim:

1. A door stop, comprising a flat base adapted to be inserted beneath a door, a cylinder disposed uprightly upon the base, the cylinder having an opening in its top end, a cylindrical top having an open lower end in which the top of the first cylinder is slidably received, the top end of said cylindrical top being closed, a flat stop lever integral with the cylindrical top and extending horizontally therefrom in spaced parallel relation with and above said base, a cup suspended in the said opening in the top of the first cylinder, and a spring positioned in and supported by said cup and housed within and pressing upwardly against the closed top of said cylindrical body.

2. A door stop of the character stated in claim 1, with coacting means between the said cylinders permitting reciprocal movement of the cylindrical top upon the first cylinder but maintaining the cylinders against relative turning movement.

3. A door stop of the character stated in claim 1, wherein the first mentioned cylinder has a longitudinally extending key way groove pressed in the wall thereof and said cylindrical top has an impressed key slidably engaging in said groove.

4. A door stop of the character stated in claim 1, wherein said cup is provided with a lateral flange engaging and resting upon the upper end of the first mentioned cylinder to maintain the cup in the said suspended position in the first mentioned cylinder.

5. A door stop of the character stated in claim 1, wherein said base includes a relatively long metal

plate with which the first mentioned cylinder is formed as an integral part, the said metal plate having a downward depression in which the said flat stop lever positions when the cylindrical top is moved downwardly to the limit of its movement, and said base further comprising a resilient friction pad covering the entire undersurface of said metal plate.

BRONISLAUS B. KAMINSKI.
